United States Patent Office

Des. 187,521
Patented Mar. 29, 1960

187,521

DRAWER PULL

Paul Westman, Lakewood, N.Y., assignor to Weber-Knapp Company, Jamestown, N.Y., a corporation of New York

Application October 30, 1958, Serial No. 53,207

Term of patent 7 years

(Cl. D10—8)

FIG.1.

FIG.2.

FIG.3.

FIG.4.

FIG.5.

Fig. 1 is a side elevational view of a drawer pull showing my new design;

Fig. 2 is a top plan view thereof;

Fig. 3 is a bottom plan view;

Fig. 4 is a section on line 4—4 of Fig. 1 in the direction of the arrows; and

Fig. 5 is an end elevational view thereof.

I claim:

The ornamental design for a drawer pull, substantially as shown.
